UNITED STATES PATENT OFFICE.

ALBERT S. GORNTO, OF NORFOLK, VIRGINIA.

SHADE-FIXTURE.

1,018,108.

Specification of Letters Patent. Patented Feb. 20, 1912.

Application filed September 14, 1911. Serial No. 649,346.

To all whom it may concern:

Be it known that I, ALBERT S. GORNTO, a citizen of the United States, and a resident of Norfolk, in the county of Norfolk and 5 State of Virginia, have invented certain new and useful Improvements in Shade-Fixtures, of which the following is a full and clear specification, reference being had to the accompanying drawings, in which—
10 Figure 1 is a front elevation of a window provided with my improved shade fixture; Fig. 2 is a side elevation thereof with the shade roller in transverse section; Fig. 3 a plan view showing the coupling of the connecting rod or bar in horizontal section; and 15 Fig. 4 a detail perspective view of one of the shade roller brackets.

The object of this invention is to provide a simple way of mounting the shade roller 20 so that it may be bodily raised and lowered so that the shade may be so adjusted as to promote ventilation and to permit light to enter the room above the shade as well as below it, as more fully hereinafter set forth.
25 In the drawing *a* designates a shade roller of the ordinary sort mounted in the usual manner in the shade brackets *b*, these brackets being mounted to slide vertically in 30 guide ways *c* fastened to the window frame, one at each side of the window. Pivottally connected to each of these brackets is a 35 depending rod *d*, the pivot being formed by bending the upper extremity of the rod downwardly and passing it through a hole in the bracket, said pivot being designated by the letter *e*. The guide way is formed 40 of a strip of sheet metal bent upon itself to form a channel *j* opening inwardly, the bottom wall of this channel being bent abruptly outwardly to form a flange *k* which bears 45 against the inner side of the adjacent shade bracket *b* and thus forms a guide and support for the same, the shade bracket being provided with a foot piece *l* adapted to fit 50 and slide in said channel *j*. These guide ways *c* extend approximately the length of the window frame, and the flanges *k* project outwardly beyond the faces of the channels, and each of these flanges is provided with a 55 series of notches *f* facing upwardly.

Each of the rods *d*, at a suitable point below its connection to the shade bracket, is bent abruptly to form a horizontal stop shoulder *g* which is adapted to rest in any 55 one of the aforesaid notches *f* and thus sup-

port the shade roller in any of its adjustable positions.

It will be observed that the shade roller may be raised and lowered by simply dislodging the stop shoulders from the notches, 60 whereupon the rods will serve as a ready means for positioning the shade roller, the manner of mounting these rods and their length permitting the operator to stand 65 away from the window and readily and evenly raise or lower the shade rollers to the point desired. It will be observed also that when the roller is adjusted to the desired position and the rods are engaged in the flanges, the depending portions of the 70 rods will lie along closely adjacent to the outer faces of the flanges and be thus protected against accidental dislodgment.

The letter *m* designates a clip which is 75 clamped removably upon the projecting end of each of the pintles of the shade-roller to prevent the same being withdrawn from their bearings in the brackets when the shade-roller is adjusted to an oblique angle 80 in the act of raising and lowering the shade-roller. The pintle holes in the brackets are of course sufficiently larger than the pintles to prevent binding should the shade-roller be thus shifted to an oblique angle in raising or lowering it. 85

Having thus fully described my invention, what I claim as new and desire to secure by Letters Patent, is—

In combination with a window frame, a 90 guide-way fastened to the frame at each side of the window and provided with a longitudinal flange extending outwardly away from the window frame and notched at intervals, a shade roller whose brackets are provided with feet which work in said guide ways, a 95 rod pivotally connected to each of said brackets and depending therefrom, each of said rods being provided with a horizontal shoulder at a point adjacent to the shade bracket, said shoulders being adapted to 100 engage the notches in said flanges and the rods being adapted to lie adjacent to the flanges.

In testimony whereof I hereunto affix my 105 signature in the presence of two witnesses.

ALBERT S. GORNTO.

Witnesses:

Mrs. W. L. PENNY,
Mrs. J. F. GORNTO.
